UNITED STATES PATENT OFFICE.

ATWELL J. BLACKFORD, OF CLEVELAND, OHIO, ASSIGNOR TO AMERICAN STOVE COMPANY, OF ST. LOUIS, MISSOURI, A CORPORATION OF NEW JERSEY.

WICK-ENGAGING MEMBER AND METHOD OF MANUFACTURING IT.

1,085,191.

Specification of Letters Patent. Patented Jan. 27, 1914.

Application filed March 9, 1912. Serial No. 682,686.

To all whom it may concern:

Be it known that I, ATWELL J. BLACKFORD, a citizen of the United States, residing at Cleveland, in the county of Cuyahoga and 5 State of Ohio, have invented a certain new and useful Improvement in Wick-Engaging Member and Method of Manufacturing It, of which the following is a specification, reference being had therein to the 10 accompanying drawing.

My invention relates to an improvement in wick engaging member, flame converters, and method of manufacturing it, for use with wick oil burners.

15 This invention relates to that class of wick oil burners of the blue flame type, wherein a flame deflector is constructed to convert the white or yellow flame into a blue flame, and is sometimes referred to as a flame converter. This type of burner to which my present invention relates has the flame converter provided with a wick engaging member and a flange thereabove to protect the wick from the radiant heat of the flame. In 20 burners of this type, heretofore known to me, the wick engaging member is in substantially the form of a flange, which extends over the top of the wick, and, in practice, it is found that with the flange the wick is 25 difficult to light and that the amount of metal contained in the flange and engaging the wick conveys and conducts a sufficient amount of heat to injuriously char the wick.

One object of my present invention is to 30 overcome the difficulty in the lighting of the wick, and the large amount of metal resting thereon by forming the wick-engaging member of a plurality of arms radiating from the body of the deflector, which exposes the

35 top of the wick between the arms to enable it to be readily lighted, and which very materially reduces the area of the metal which is in engagement with the top of the wick.

Another object of my present invention is 40 to construct the lower portion of the deflector, the wick engaging members and the flange thereabove of a single piece of metal.

A further object of my invention pertains 45 to the method of forming the lower body portion of the deflector, the wick-engaging arms and the flange thereabove from a single piece of metal.

In the accompanying drawings—Figure 1 is a vertical central sectional view of the

burner portion of that type of wick blue flame burner to which my present invention pertains. Fig. 2 is an inverted perspective view of my improved flame deflector or converter. Fig. 3 is a sectional view showing the shape of the piece of metal at one stage 55 of converting it into a wick engaging member with a flange thereabove. Fig. 4 is a similar sectional view showing the next step 60 in forming the flame engaging member and the flange thereabove. Fig. 5 is a sectional view of the completed flame engaging member 65 with the flange thereabove.

The type of wick blue-flame oil stoves to which this invention relates, is now so well-known to those skilled in the art that a general description thereof will be sufficient to enable my improvement to be understood.

Referring now to the drawings in which like reference characters denote the same parts, 1 is a wick which extends down into 70 a chamber or wick space 2. This wick 1 is vertically adjustable by means of any suitable form of wick-raiser 3.

Referring now to the flame deflector or converter, 4 is a vertical flange which constitutes the lower body portion of the converter, and this flange has secured therein a suitable spider 5 having an opening 6 in which a rod 7 loosely fits. The lower end of this rod 7 is firmly supported by a bracket 8, extending from the inner wick tube 9, and its upper end is provided with a detachable screw-eye or nut 10, for limiting the upper movement of the converter and also to permit the converter to be removed. The 90 spider 5 projects above the upper end of the flange 4 and supports an inverted dish-shaped cap 11.

My present invention relates to the construction of the member 4. This member 4 95 comprises, as stated, a vertical flange and has its upper end turned outward to form an outwardly extending annular flange at the upper end of the member. As shown in Fig. 3, the upper portion of the flange 4, 100 is provided with a plurality of vertical openings 13. Fig. 3 shows the form of the member at one stage of the construction of the completed device, shown in Fig. 5. It is common to form from a single piece of metal 105 a member having a vertical flange 4, and an outwardly extending flange 12, as shown in Fig. 3, and the manner of also forming it

need not be described. The parallel openings 13 are cut in the vertical flange 4, by any suitable die, which is so well understood that a description thereof is unnecessary.

5 After the member is formed, as shown in Fig. 3, the arms 14 are bulged outward into approximately a U-shape, as shown in Fig. 4, and the bulging or bending outwardly of the arms 14 draws the flange downwardly 10 so that the member is shortened. The next step in forming the member 4, is making a short bend 15 at the center of the arms 14, as shown in Fig. 5, and pressing the doubled portion of the arms together, as also shown 15 in this figure of the drawing. This operation still further shortens the member 4 and it also leaves small openings *a* between the arms 14, as clearly shown in Figs. 1 to 5.

The flange 12 is provided with a series of 20 openings 16, which are annularly arranged on the flange, as shown in Fig. 2. The openings 16 may be formed at any desired stage in the making of the completed member, though preferably they are formed when the 25 member is in the shape indicated in Fig. 3 and before the arms 14 are bent.

Referring now to Fig. 2, attention is directed to the spaces *b* between the arms 14, which leave the wick exposed at these points 30 and enable it to be readily lighted. The spaces *b* between the arms which lie in a vertical plane above the space *c*, afford air-passages for the passage of the air from the inner wick tube 9, past the inner side of the wick 35 and then across its top.

The flange 12, located above and adjacent the arms 14, serves to deflect the air outward over the upper end of the wick between the arms 14, a portion of this air passing upward through the openings 16 formed in said flange 12. This flange 12 therefore performs the treble function of intercepting and protecting the upper end of the wick from the radiant heat above; directing a current of air outward over the upper end of the wick and allowing a portion of the air to pass through the flange to supply air to the escaping burning gases above to afford a proper mixture of air therewith. The air 50 passing through the openings in the flange 12 also materially cools the flange which, thereby, better reacts and performs its func-

tion as a radiant heat interceptor for the upper end of the wick.

Having thus described my invention, what 55 I claim and desire to secure by Letters Patent is:

1. The method of forming a wick engaging member for flame converters, consisting in providing an annular flange, cutting 60 therein a plurality of openings around its circumference to provide a plurality of longitudinally arranged arms, bulging the said arms outward and bending them at the center back upon each other to form a plurality of radially outwardly extending arms. 65

2. The method of forming a wick engaging member for flame converters having an outwardly extending flange thereabove, consisting in providing an annular flange with 70 an outwardly extending flange at its upper end and vertically arranged openings in the flange around its circumference and below the said outwardly extending flange to form vertically arranged arms, bulging the said 75 arms outward and finally bending the arms at their center and doubling them back on each other to form a plurality of outwardly extending arms below the said outwardly extending flange. 80

3. The method of forming a wick engaging member for flame converters having an outwardly extending flange thereabove, consisting in providing a cylindrical member 85 provided with an outwardly extending flange at its upper end and vertically arranged openings in the cylindrical member around its circumference and below said outwardly extending flange to form vertically arranged arms, bulging the said arms outwardly and finally bending the arms at their 90 center and doubling them back on each other to form a plurality of outwardly extending arms below said outwardly extending flange with an opening between each arm communicating with the interior of the cylindrical member. 95

In testimony whereof I hereunto affix my signature in the presence of two witnesses.

ATWELL J. BLACKFORD.
